CLAIM

The ornamental design for a bottle cap, as shown and described.

DESCRIPTION

FIG. 1 is a top, front, and right perspective view of a bottle cap showing the new design.

FIG. 2 is a bottom, rear, and right perspective view of the bottle cap showing the new design.

FIG. 3 is a top, rear, and left perspective view of the bottle cap showing the new design.

FIG. 4 is a top view of the bottle cap showing the new design.

FIG. 5 is a bottom view of the bottle cap showing the new design.

FIG. 6 is a left side view of the bottle cap showing the new design (the right side view being a mirror image thereof); and,

FIG. 7 is a front view of the bottle cap showing the new design (the rear view being a mirror image thereof).

Within the drawings, the even spaced dash-dash lines, and the areas within the dash-dash lines, show unclaimed portions of the bottle cap and form no part of the claimed design. The surface shading lines are provided to indicate any contour or curvature of the surfaces.
